POLISHING MACHINE

Ernest E. Murray, Detroit, Mich.

Application July 22, 1940, Serial No. 346,730

6 Claims. (Cl. 51—166)

This invention relates to polishing machines. More particularly, it relates to a simple, novel, compact, and easily adjustable polishing or buffing unit which may be combined with a plurality of identical units associated with a conveyer or dial type feed mechanism to produce apparatus for automatically polishing or buffing irregularly shaped parts.

As is conventional in apparatus of this general character, the parts to be polished or buffed are mounted on a conveyer or turn-table to be fed past a plurality of buffing or polishing wheels which are arranged at various angles or inclinations so that when the part has passed all of the units, the surface will be completely polished or buffed.

The primary object of the present invention is to provide a machine which is simple, compact, and easily and conveniently adjustable in order to dispose the polishing wheel at the desired inclination and position with respect to the work to be operated upon.

The machine contemplates the provision of means for mounting a motor together with drive mechanism for rotating a buffing or polishing wheel in such a way that the wheel may be universally adjusted throughout all positions without in any way interfering with the drive between the motor and the wheel.

Still further, the invention contemplates the provision of a machine in which the above mentioned adjustments may be made simply and rapidly and in which the machine, having once been adjusted, will remain in the desired adjusted position.

Many other objects, advantages, and features of the present invention will become clearly apparent when considered in connection with the following specification and the drawings forming a part thereof.

In the drawings:

Figure 1 is a side view of the machine with parts broken away to illustrate more clearly the parts thereof.

Figure 2 is a front elevational view of the machine with parts broken away to illustrate the mounting and adjustment of the various members of the machine.

Figure 3 is a top plan view of the machine with portions broken away to illustrate more clearly the construction and arrangement of parts.

Figure 4 is a transverse sectional view taken substantially along the line 4—4 of Figure 1, illustrating in detail the drive mechanism for the

wheel together with the adjustment means for maintaining proper tension on the drive belts.

Figure 5 is a vertical sectional view taken substantially on the line 5—5 of Figure 2 illustrating in detail the construction of the hood surrounding the wheel and the means for ventilating the same.

Figure 6 is a vertical sectional view taken substantially on the line 6—6 of Figure 3 illustrating in detail the means for adjusting the pressure of the wheel against the work upon which the wheel operates.

Figure 7 illustrates in fragmentary top plan, similar to Figure 3, a modified form of the invention in which additional means are provided for effecting limited oscillation of the polishing wheel with respect to the work.

Figure 8 is a side elevational view with parts broken away illustrating in further detail the modified form of the invention shown in Figure 7.

With more particular reference to the drawings, it will be readily appreciated and understood that the unit illustrated is merely one of a plurality of identical units which may together be arranged in operative position with respect to a conveyer or turntable upon which the parts to be finished are mounted. It will further be readily appreciated that the apparatus of the present invention is designed and intended for polishing the surface of irregularly shaped parts and that each of the units is adjusted to a position so that it will polish or buff a certain predetermined portion of the irregularly shaped part to be finished.

As is conventional in apparatus of this general character, the various units making up the machine as a whole are adjusted to various different positions so that as the part passes each of the units, a portion of its surface will be buffed or polished and that if a cycle of operation is completed, the article to be polished will have been completely finished.

In the particular specific embodiment of the invention illustrated in the drawings, the device disclosed comprises a relatively heavy base member 1 which is adapted to rest on the floor adjacent the conveyer or turntable (not shown) which carries the parts to be polished continually past the unit. This base member has journalled for rotation longitudinally therein a feed screw 3 which is conveniently rotated by means of a hand crank 9. Threadably received on the feed screw 3 is a nut 10 which is anchored to an upper base member 11 which, as shown, is slidably mounted on the base member 1. The upper base member 11 is formed to provide anchorage

for a pair of uprights 12 on which is slidably mounted a yoke 13 which serves to mount the polishing head structure hereinafter described in detail.

It will be readily apparent that a hydraulic jack or other elevating member may be disposed on the upper surface of the base member 11 between the uprights 12 in a position to engage the lower side of the yoke 13 in order to vary the vertical position of the yoke as may be desired. The yoke 13 serves to mount a ring member 14 which is provided with oppositely extending trunnions 15 and 16 journaled for rotation in the yoke. As is clearly shown in Figure 3 of the drawings, the trunnion member 16 extends through the yoke member and has anchored thereto a worm wheel 17 which meshes with a worm 18. The worm is mounted on a shaft 19 journaled in a plurality of bosses 20 integrally formed with the yoke member 13. The shaft at its rearward end is provided with a hand crank 21.

From the foregoing, it will be apparent that the ring member 14 can be rotated about the trunnions 15 and 16 through 360° of movement by rotation of the crank 21. A circular table 25 is rotatably mounted within the ring 14 and, as is clearly seen in Figure 3 of the drawings, the periphery of the table is provided with teeth, thus forming the table as a disc-like worm wheel. The teeth on the periphery of the table mesh with a worm 26 on a shaft 27, which shaft is journaled for rotation in suitable bosses 28, preferably formed integral with the ring member 14. Shaft 27 may be easily and conveniently rotated by means of a hand crank 29. It will, therefore, be seen that rotation of the crank 29 will serve to rotate the table 25 about an axis substantially perpendicular to the axis about which the ring is rotatable. It will also be apparent that the table 25 may be rotated by different means through an angularity of 360° and since the ring member as above described may also be rotated through 360° by means of crank 21, it is possible by adjustment between these two members to dispose the table in any desired position. In other words, it is clear that the table 25 is conveniently adjustable for universal movement. Likewise, it will be appreciated that due to the fact that the adjusting means comprises worm gearing, the table when once adjusted will be maintained locked in predetermined desired position.

Mounted on the table 25 is an electric motor 30 which may be supplied with current by a suitable flexible cord (not shown) and as is seen in Figure 1 of the drawings, the motor 30 is mounted by means of a hinge 31 and adjusting stud 32 in order to tighten the drive belts from the motor when the same becomes necessary. The motor has anchored directly to the shaft thereof a pulley 32 which serves to drive the mechanism hereinafter described. Projecting downwardly from the opposite side of the table 25 on which the motor is mounted is a rigid arm 35 which has pivoted thereto an arm 36 by means of a shaft 37. Journaled for rotation on the shaft 37 is a pulley 38 which by means of a plurality of drive belts 39 is drivingly connected with the pulley 32 of the motor. As is seen in Figure 3 of the drawings, these belts extend through a suitable aperture in the table 25.

As is clearly seen in Figure 4 of the drawings, the arm 36 has an extensible portion 40

adjustably connected thereto by means of bolts 41 in order that the effective length of this arm may be increased or shortened as may be desired. The outer end of the arm 40 is bifurcated to provide a pair of bearings 42 in which is journaled a shaft 43 which carries a pulley 44. This pulley 44 is connected by means of driving belts 45 with the pulley 38 and it will be seen that these belts may be maintained at the proper adjustment by increasing the effective length of the arm composed of the members 36 and 40.

The shaft 43 carries a polishing or buffing wheel 50 anchored thereto in conventional manner which wheel is preferably partially surrounded by a dust receiving housing 51 anchored to the plate member 25 as best illustrated in the sectional view of Figure 5. This housing has communicating therewith a flexible conduit 52 which may conveniently be connected to an exhaust blower (not shown) to exhaust dust and dirt created during the polishing operation.

In view of the fact that the axis of rotation of the pulley 38 coincides with the axis of pivotal movement of the arm 36, it will be seen that the arm supporting the polishing wheel 50 may be adjusted throughout a substantial angular degree of movement without in any way interfering with the drive thereof by the motor 30. The arm 36 may be adjusted to the predetermined desired position by means of an adjusting screw rod 60 which is connected by means of a compression coil spring 61 and abutting a suitable projection 69 on the member 40. In addition, the member 40 is connected by a tension coil spring 70 directly to the plate 25 in order that as the screw 60 is unscrewed, the coil spring 70 will draw the member 40 toward the plate 25. This screw rod 60 extends upwardly through a suitable aperture in the table 25 as is clearly seen in Figure 6 and passes through a split nut comprising separate halves 62 and 63. The nut half 62 is rigidly bolted to the table by means of a screw 64 and is provided with a semi-cylindrical groove for reception of the screw rod 60. The nut half 63 is mounted for pivotal movement by means of a pin 65 and has a semi-cylindrical internally threaded recess adapted to engage the screw 60.

From the foregoing, it will be seen that in order to effect rapid adjustment of the screw rod, the nut half 63 may be swung around its pivot and the polishing wheel bodily elevated out of operative position.

This is a particularly desirable feature of the present invention because it permits rapid elevation of the polishing wheel away from operative position when it becomes necessary to change wheels and at the same time permits the use of a relatively fine screw thread for accurate adjustment of the position of the polishing wheel when located in the position to engage the work.

In operation of the apparatus, it will be seen that a plurality of units of the type described above can be placed with their bases on the floor adjacent a conveyer or turntable carrying the articles to be polished. The polishing wheel 50 may be bodily moved in a horizontal direction by rotation of the feed screw 8 operated by the crank 9. The yoke 13 may be adjusted on the uprights 12 to the predetermined desired vertical position. By rotation of the shaft 19 by means of the crank 21, the table which carries the motor, polishing wheel, and interconnecting drive mechanism may

be swung to desired position about a generally horizontal axis provided by the trunnions 15 and 16. In addition, rotation of the crank 28 will serve to adjust the position of the table 25 about an axis substantially perpendicular to the axis of the trunnions 15 and 16 thereby permitting universal movement of the position of the polishing wheel. Through the medium of cranks 21 and 29, the polishing wheel may be located at the desired angular position with respect to the work passing on the conveyer with which the work is associated. The pressure of the wheel against the work may be accurately adjusted by means of the screw rod 62 and it will be seen that when the split nut 63 is swung upwardly, the polishing wheel may be rapidly and bodily raised out of operative position to facilitate rapid changes of the polishing wheel.

With reference to the modified form of the invention shown in Figures 7 and 8, it will be readily seen that this embodiment of the invention is designed and intended for installations where it is desired to impart a lateral oscillatory movement to the polishing wheel while in engagement with the work to distribute wear more evenly over the surface of the polishing wheel and at the same time permit the polishing wheel to effectively contact a larger area of the work surface. In this form of the invention, a slightly modified form of table 70 is employed which, similar to the table 25, is provided with teeth at its periphery to constitute a work wheel adapted to be rotated by means of the worm wheel 26, shaft 27, and crank 29 in the same manner as has been described above in connection with the preferred embodiment of the invention. This table has at its lower side a shaft support member 71 rigidly secured to the table which provides means for rotatably mounting a shaft 72. The shaft 72 serves at its lower end to support an arm 73 which provides the pivotal connection 31 of the arms 36 and 40 which together provide means for mounting the polishing wheel 50 as has been described above.

On the upper side of the table is mounted an electric motor 75 which by means of an eccentric 76 and link 77 connects with a crank 78 on the upper end of the shaft 72. It will, therefore, be apparent that as the motor 75 rotates, it will impart to the shaft 72 a limited oscillatory movement which will serve to effect a relatively limited oscillatory lateral movement of the polishing wheel. This lateral oscillatory movement is sufficiently limited in extent so that it does not materially affect the tension of the driving belts, and it will be seen that the magnitude of this oscillatory movement can be carefully and adequately controlled by varying the magnitude of the eccentric 76.

Lateral oscillatory movement of the polishing wheel 50 will increase the effective area of the polishing action of this wheel and will at the same time distribute wear more uniformly over the peripheral surface thereof.

It will likewise be readily apparent that if the motor 75 is not operated, the shaft 72 will be relatively rigidly locked in position in order that the apparatus will then function substantially in the same manner as that described in connection with the preferred embodiment of the invention.

It will be readily appreciated that many other and further modifications of the invention may be made without departing from the spirit thereof as set forth in the subjoined claims.

What is claimed is:

1. A polishing machine including in combination, a universally adjustable plate, a motor mounted on one side of said plate, means on the opposite side of said plate for supporting a polishing wheel, means drivingly interconnecting said motor and said polishing wheel, an adjusting screw for varying the distance of said polishing wheel from said plate, and means for releasing said adjusting screw to permit rapid bodily movement of said polishing wheel with respect to the work, said last named means including a split nut adapted to be positioned in embracing relationship to said screw, one of the split sections of the nut being pivotally mounted 15 with respect to the other section.
2. In a machine of the type described, in combination, an assembly for a rotating work tool, including an arm mounted for oscillation about a fixed axis, a tool holding spindle mounted in 20 said arm parallel to said axis, a pulley concentric with said axis, a stationary motor support having a motor mounted thereon, means driving said pulley from said motor, means driving said spindle from said pulley, springing means 25 supporting said arm against gravity at an angle with respect to the vertical and springing means including the first named springing means opposing oscillation of said arm out of its selected position, means for adjustably rotating said assembly through 360° about an axis generally perpendicular to the axis of said tool holding spindle, and additional means for adjustably rotating said assembly through 360° about an axis generally parallel to the axis of said tool 30 holding spindle.
3. In a machine of the type described, in combination, an assembly for a rotating work tool, including an arm mounted for oscillation about a fixed axis, a tool holding spindle mounted in 35 said arm parallel to said axis, a pulley concentric with said axis, a stationary motor support having a motor mounted thereon, said arm being adjustable in length, said motor support being adjustable toward and away from said axis, means driving said pulley from said motor, means driving said spindle from said pulley, springing means supporting said arm against gravity at an angle with respect to the vertical and springing means including the first named 40 springing means opposing oscillation of said arm out of its selected position, means for adjustably rotating said assembly through 360° about an axis generally perpendicular to the axis of said tool holding spindle, and additional means for adjustably rotating said assembly through 360° about an axis generally parallel to the axis of said tool holding spindle.
4. In a machine of the type described, in combination, an assembly for a rotating work tool, including an arm mounted for oscillation about a fixed axis, a tool holding spindle mounted in said arm parallel to said axis, a pulley concentric with said axis, a stationary motor support having a motor mounted thereon, means driving said pulley from said motor, means driving said spindle from said pulley, springing means supporting said arm against gravity at an angle with respect to the vertical and springing means including the first named springing 45 means opposing oscillation of said arm out of its selected position, means for adjustably rotating said assembly through 360° about a horizontal axis generally perpendicular to the axis of said tool holding spindle, and additional means for adjustably rotating said assembly through 360° about an axis generally parallel to the axis of said tool holding spindle.
5. In a machine of the type described, in combination, an assembly for a rotating work tool, including an arm mounted for oscillation about a fixed axis, a tool holding spindle mounted in said arm parallel to said axis, a pulley concentric with said axis, a stationary motor support having a motor mounted thereon, means driving said pulley from said motor, means driving said spindle from said pulley, springing means supporting said arm against gravity at an angle with respect to the vertical and springing means including the first named springing 50 means opposing oscillation of said arm out of its selected position, means for adjustably rotating said assembly through 360° about a horizontal axis generally perpendicular to the axis of said tool holding spindle, and additional means for adjustably rotating said assembly through 360° about an axis generally parallel to the axis of said tool holding spindle.
6. In a machine of the type described, in combination, an assembly for a rotating work tool, including an arm mounted for oscillation about a fixed axis, a tool holding spindle mounted in said arm parallel to said axis, a pulley concentric with said axis, a stationary motor support having a motor mounted thereon, means driving said pulley from said motor, means driving said spindle from said pulley, springing means supporting said arm against gravity at an angle with respect to the vertical and springing means including the first named springing 55 means opposing oscillation of said arm out of its selected position, means for adjustably rotating said assembly through 360° about a horizontal axis generally perpendicular to the axis of said tool holding spindle, and additional means for adjustably rotating said assembly through 360° about an axis generally parallel to the axis of said tool holding spindle.
7. In a machine of the type described, in combination, an assembly for a rotating work tool, including an arm mounted for oscillation about a fixed axis, a tool holding spindle mounted in said arm parallel to said axis, a pulley concentric with said axis, a stationary motor support having a motor mounted thereon, means driving said pulley from said motor, means driving said spindle from said pulley, springing means supporting said arm against gravity at an angle with respect to the vertical and springing means including the first named springing 60 means opposing oscillation of said arm out of its selected position, means for adjustably rotating said assembly through 360° about a horizontal axis generally perpendicular to the axis of said tool holding spindle, and additional means for adjustably rotating said assembly through 360° about an axis generally parallel to the axis of said tool holding spindle.
8. In a machine of the type described, in combination, an assembly for a rotating work tool, including an arm mounted for oscillation about a fixed axis, a tool holding spindle mounted in said arm parallel to said axis, a pulley concentric with said axis, a stationary motor support having a motor mounted thereon, means driving said pulley from said motor, means driving said spindle from said pulley, springing means supporting said arm against gravity at an angle with respect to the vertical and springing means including the first named springing 65 means opposing oscillation of said arm out of its selected position, means for adjustably rotating said assembly through 360° about a horizontal axis generally perpendicular to the axis of said tool holding spindle, and additional means for adjustably rotating said assembly through 360° about an axis generally parallel to the axis of said tool holding spindle.
9. In a machine of the type described, in combination, an assembly for a rotating work tool, including an arm mounted for oscillation about a fixed axis, a tool holding spindle mounted in said arm parallel to said axis, a pulley concentric with said axis, a stationary motor support having a motor mounted thereon, means driving said pulley from said motor, means driving said spindle from said pulley, springing means supporting said arm against gravity at an angle with respect to the vertical and springing means including the first named springing 70 means opposing oscillation of said arm out of its selected position, means for adjustably rotating said assembly through 360° about a horizontal axis generally perpendicular to the axis of said tool holding spindle, and additional means for adjustably rotating said assembly through 360° about an axis generally parallel to the axis of said tool holding spindle.
10. In a machine of the type described, in combination, an assembly for a rotating work tool, including an arm mounted for oscillation about a fixed axis, a tool holding spindle mounted in said arm parallel to said axis, a pulley concentric with said axis, a stationary motor support having a motor mounted thereon, means driving said pulley from said motor, means driving said spindle from said pulley, springing means supporting said arm against gravity at an angle with respect to the vertical and springing means including the first named springing 75 means opposing oscillation of said arm out of its selected position, means for adjustably rotating said assembly through 360° about a horizontal axis generally perpendicular to the axis of said tool holding spindle, and additional means for adjustably rotating said assembly bodily.

through 360° about an axis generally parallel to the axis of said tool holding spindle.

5. A machine of the type described comprising, in combination, an upright standard, a supporting member mounted on said standard and projecting to one side thereof, an annular member, pivot means connecting said annular member to said supporting member, a plate member, a motor mounted on said plate member, support means on the opposite side of said plate member from the side on which the motor is mounted, a rotatable work wheel adjustably mounted with respect to said plate member by said support means, means drivingly interconnecting said motor and said wheel, and means rotatably connecting said plate member to said annular member for rotation about an axis at substantially 90° to the axis of the pivot means.

6. A machine of the type described comprising,

ing, in combination, an upright standard, a supporting member mounted on said standard and projecting to one side thereof, an annular member, pivot means connecting said annular member to said supporting member, a plate member, a motor mounted on said plate member, support means on the opposite side of said plate member from the side on which the motor is mounted, a rotatable work wheel adjustably mounted with respect to said plate member by said support means and disposed within the confines of said annular member, means drivingly interconnecting said motor and said wheel, and means rotatably connecting said plate member to said annular member for rotation about an axis at substantially 90° to the axis of the pivot means.

ERNEST E. MURRAY.
